DECK LID HINGE WITH ADJUSTABLE SPRING COUNTERBALANCE

Thomas J. Hosea, Detroit, Mich., assignor to General Motors Corporation, Detroit, Mich., a corporation of Delaware

Application May 11, 1954, Serial No. 428,923

6 Claims. (Cl. 16—190)

This invention relates to a lid hinge and hold-open, and more particularly to a hinge and adjustable hold-open for the deck lid of an automobile.

Hingedly mounted deck lids are provided with counterbalance spring means which facilitate initial opening movement of the deck lid and which increase in effectiveness as the deck lid approaches open position and hold the deck lid in its fully open position. Because of variations in spring strength and in the size and weight of different deck lids, it is difficult to obtain a uniform counterbalance effect in assembly line production. This invention provides a simple and effective adjustment means whereby the counterbalance force exerted by the spring may be varied in fixed steps to obtain proper operation despite variations in spring strength, size and weight of deck lids, and the like. According to the invention, a support bracket depends from the hinge arm for anchoring one end of the counterbalance spring, the bracket having a plurality of spaced anchor notches for adjusting the spring strength in fixed steps so that desired counterbalance action may be obtained after the automobile has been assembled.

Other features and advantages of the invention will be apparent from the following description and from the drawings, in which:

Fig. 1 is a fragmentary rear perspective view of an automobile embodying the invention;

Fig. 2 is an enlarged fragmentary longitudinal vertical section through one of the deck lid hinges, the deck lid being shown in open position in solid lines and in closed position in broken lines;

Fig. 3 is a horizontal section taken along the line 3—3 of Fig. 2, the counterbalance spring being removed; and

Fig. 4 is a further enlarged section corresponding to a portion of Fig. 2.

Referring now more particularly to the drawings, an automobile designated generally as 10 in Fig. 1 has a body 11 with a deck compartment 12 and a deck lid 13 therefor. The deck lid is hingedly mounted on the body, being carried on spaced gooseneck hinge straps 15, each of which is pivotally mounted in a channel-shaped elongated hinge box 16.

Since the hinge straps 15 are secured to the deck lid 13 closely adjacent the forward edge thereof, the leverage of the deck lid is high, and counterbalance springs are provided to offset the weight of the deck lid. Preferably, these springs are arranged to exert enough counterbalance force almost to overcome the weight of the deck lid when the deck lid is nearly closed, and to increase in effectiveness and more than overcome the weight of the deck lid as the deck lid approaches open position, so that the springs will hold the deck lid open as shown in Fig. 1. This varying counterbalance action is obtained by mounting the springs so that the moment arm of the springs change as the deck lid moves toward open position.

Each hinge and counterbalance means is similar and only one will be described. As shown in Fig. 2, strap 15

5

2

is pivoted upon a pin 18 which extends between the opposite walls of the elongated hinge box 16 mounted on the undersurface of the body panel 11 and closely adjacent the forward edge of the deck compartment opening 12, and the gooseneck form of strap 15 enables the deck lid 13 to move upwardly and forwardly when opened to provide free access to the compartment 12. A rubber bumper 19 on a pin 19a limits opening movement of the deck lid 13.

Each hinge is provided with counterbalance spring means and extensible supporting guide means therefor comprising aligned telescoping spring supporting links 20 and 21, each provided with a slot 20a and 21a, respectively. A pin 22 is secured to the end of link 21 and projects through the slot 20a, and a similar pin 23 is secured to the end of link 20 and projects through the slot 21a so that the links, while held in alignment, may be extended or retracted within limits defined by the length of the slots as the deck lid is opened or closed. The forward end of link 20 is pivoted on a pin 24 mounted between the hinge box walls, and the links support a compression spring 25, the forward end of the spring seating against a collar 26 and the rear end of the spring seating against a shoulder formed by an enlarged head portion 27 at the end of link 21.

The structure described above is old. In the past, the rear end of the counterbalance spring (or the rear end of the support and guide link 21) has been nonremovably secured to a support bracket depending rigidly from the hinge strap, and there has been no means of adjustment to compensate for variations in spring strength, size and weight of different deck lids, and the like. Instead of securing the rear end of the counterbalance spring means fixedly to the support bracket as has been done in the past, an adjustment means is provided so that the effective counterbalance force exerted by the spring 25 may be varied in fixed steps.

A support bracket 30 is riveted to the underside of strap 15 and depends downwardly from said strap within the box 16. The bracket 30 is formed with spaced notches 31, 32 located in the forward side of the bracket adjacent the free or depending end thereof. A pin 33 which projects laterally from the rear end of link 21 is adapted to seat in a selected one of the notches 31, 32 to complete the connection between the counterbalance spring means and the hinge arm 15. In the drawings, pin 33 is shown in notch 32 which is remote from the pivotal axis 18 of the hinge arm so that the moment arm of the spring, when the deck lid is open, is at a maximum. This arrangement provides maximum counterbalance spring force. If less counterbalance spring force is desired, the pin 33 may be removed from the notch 32 and seated in the notch 31, and this may be done during the assembly of the automobile or at any time after the automobile is assembled. In order to shift the pin 33 from one notch to the other, the stop pin 19 is removed so that the deck lid 13 may be swung open beyond its illustrated normal fully open position. Since extension of the spring support links 20 and 21 is limited by the pin and slot interconnection between the links, the bracket 30 will be disconnected from the pin 33, and the pin may be rearranged in either selected notch.

The stop pin 19 may be provided at its end with a readily removable key or clip (not shown) of conventional construction so that the stop pin may be easily removed to permit adjustment of the spring force.

While I have shown and described one embodiment of my invention, it is capable of many modifications. Changes, therefore, in the construction and arrangement may be made without departing from the spirit and scope of the invention as set forth in the appended claims.

I claim:

1. In an automobile having a body with a deck compartment and a deck lid therefor, a hinge and counterbalance for the deck lid, including: a pivotally mounted hinge member connecting the lid to the body; a compression spring; a pair of telescoping links carrying said spring; means for pivotally connecting one end of one of said links to said body; and a support bracket depending from said hinge member for anchoring one end of the other link, said bracket having a plurality of spaced anchor notches each adapted to engage a portion of the other link whereby said other link may be seated in a selected notch to adjust the spring strength in fixed steps.
2. In an automobile having a body with a deck compartment and a deck lid therefor, a hinge and counterbalance for the deck lid, including: a hinge member pivotally connected to the body within the compartment and rigidly connected to the lid; a compression spring in the compartment; an extensible supporting guide mounted on the spring; means pivotally connecting one end of said guide to said body; and a support bracket depending from said hinge member for anchoring the other end of said guide, said bracket having a plurality of spaced anchor notches selectively adapted to seat the other end of said extensible guide for adjusting the spring strength in fixed steps.
3. In an automobile body having an opening and a closure for said opening, a hinge and counterbalance for said closure comprising, a hinge member swingably mounted on said body and secured to said closure, compression spring means, guide means seating said spring means, and connector means connecting said guide means between said hinge member and said body and including a plurality of spaced anchor notches for selectively seating said guiding means to adjust the spring strength in fixed steps, said spring means urging said guide means against said connector means to counterbalance the weight of said closure during movement thereof.
4. A hinge and counterbalance in accordance with claim 3 wherein said connector means comprises a support bracket secured to said hinge member and projecting therefrom for anchoring one end of said guide means.
5. In an automobile body having an opening and a closure for said opening, a hinge and counterbalance for said closure comprising, a hinge member swingably mounted on said body and secured to said closure, a guide extendable to a predetermined extent, means swing-

- 5 thereto under the action of said spring whereby said guide and spring counterbalance the weight of said closure, said connector means including a plurality of spaced anchor notches for selectively seating the other end of said guide to thereby selectively adjust the spring strength in fixed steps, and means limiting the swing movement of said closure to a predetermined position to retain the connection between said guide and said connector means by preventing movement of said connector means out of engagement with said other end of said guide when said guide is extended.
- 10 6. In an automobile body having an opening and a closure for said opening, a hinge and counterbalance for said closure comprising, a hinge member swingably mounted on said body and secured to said closure, a guide extendable to a predetermined extent, means swingably mounting one end of said guide on said body, a compression spring seated on said guide and exerting a yieldable force to extend said guide, connector means on said hinge member for connecting the other end of said guide
- 15 20 25 30 35 40 45 thereto under the action of said spring whereby said guide and spring counterbalance the weight of said closure, said connector means including a plurality of spaced anchor notches for selectively seating the other end of said guide to thereby selectively adjust the spring strength in fixed steps, and means limiting the swinging movement of said closure to a predetermined position to retain the connection between said guide and said connector means by preventing movement of said connector means out of engagement with said other end of said guide when said guide is extended to said predetermined extended position, said limiting means being movable to allow said closure to move to a position wherein said guide may be moved out of engagement with the selected one of said notches and into engagement with another of said notches to thereby change the spring strength in a fixed step.
